[57] CLAIM

The ornamental design for a multiposition peghook bracket, as shown and described.

DESCRIPTION

FIG. 1 is a perspective view of the multiposition peghook bracket according to the invention showing the top, front and right side thereof;

FIG. 2 is a front elevation;

FIG. 3 is a right side elevation as seen from the right of FIG. 2, the left side elevation being a mirror image of this right side elevation;

FIG. 4 is a plan view of the top as seen from the top of FIG. 2; and

FIG. 5 is a section on section line 5—5.

The rear and base not shown are plain.

FIG. 1

FIG. 2

FIG. 3
